UNITED STATES PATENT OFFICE

148,458

DESIGN FOR A KEYBOARD FOR CALCULATING MACHINES OR SIMILAR ARTICLES

Hugh L. Clary, Pasadena, and Robert E. Boyden,
 Los Angeles, Calif., assignors to Clary Multiplier Corporation, Los Angeles, Calif., a corporation of California

Application November 10, 1945, Serial No. 123,664

Term of patent 14 years

(Cl. D64—11)

To all whom it may concern:

Be it known that we, Hugh L. Clary and Robert E. Boyden, both citizens of the United States and residents of the city of Pasadena and the city of Los Angeles, respectively, and both in the county of Los Angeles and State of California, have invented a new, original, and ornamental Design for a Keyboard for Calculating Machines or Similar Articles, of which the following is a specification, reference being had to the accompanying drawing, forming part thereof, and wherein:

Figure 1 is a perspective view of a keyboard for calculating machines or similar articles, showing our new design,

Figure 2 is a plan view thereof, and

Figure 3 is a side elevational view of a portion of said keyboard and is taken along the lines 3—3 of Fig. 2.

The essential features of our design reside in the parts shown in full lines and include the specific configurations and arrangement of the keys and bars surrounding the same.

We claim:

The ornamental design for a keyboard for calculating machines or similar articles, substantially as shown and described.

HUGH L. CLARY.
 R. E. BOYDEN.
